UNITED STATES PATENT OFFICE.

MINOTT W. SEWALL, OF ROSELLE, NEW JERSEY.

APPARATUS FOR REDUCING TEMPERATURE OF SUPERHEATED STEAM.

No. 834,589.

Specification of Letters Patent.

Patented Oct. 30, 1906.

Application filed March 28, 1906. Serial No. 308,385.

To all whom it may concern:

Be it known that I, MINOTT W. SEWALL, a citizen of the United States, residing at Roselle, in the county of Union and State of New Jersey, have invented certain new and useful Improvements in Apparatus for Reducing the Temperature of Superheated Steam, of which the following is a specification, reference being had therein to the accompanying drawings.

Where steam from a single source or place of generation is supplied to a number of different pieces of machinery or apparatus, it is frequently desirable that the temperature of the steam should be different at the different places of delivery.

The purpose of this invention is to effect an automatic reduction of the temperature of highly-superheated steam which is supplied from the superheaters or the steam-main of a plant, so that steam of a lower degree of temperature may be available where this is necessary or desirable.

In the accompanying drawings I have illustrated two forms of apparatus embodying my invention and designated, respectively, Figure 1 and Fig. 2, these being sectional views with parts in elevation, illustrating sufficient apparatus for a clear understanding of the principle of my invention.

Referring to the drawings, A represents a steam plant, which may be of any usual or approved construction, that illustrated comprising a water-tube boiler *a* and a steam dome or drum *a'*, with other accessory parts, which it is unnecessary to refer to in detail.

B represents as a whole a cooler of the surface-condenser type. This cooler is formed with the end chambers *b b*, connected by the pipes *b²*, these parts being adapted to contain water. There is between the end chambers *b* an intermediate space *b'*, traversed by the water-tubes *b²*, and through this space *b'* the steam whose temperature is to be reduced is caused to pass.

Referring now particularly to the apparatus illustrated in Fig. 1, C represents a pipe connecting the water-space of the steam-generator A with the water-space of the cooler B. In this pipe there is placed a stop-valve *c'*. D represents a pipe connecting the steam-space of the generator with the steam-space of the cooler, and in this pipe there is situated a stop-valve *d'*. It will be

observed that the cooler is situated below the normal minimum or low-water level of the boiler or steam-generator, so that when in use the cooler is always flooded with water from the boiler the temperature of which will be approximately that of the water in the boiler. The two end chambers *b b* of the cooler are united not only by the water-tubes *b²*, but also by a connection or conduit comprising a circulating-pipe *f* and an enlargement or separating-chamber F, which latter is connected at *f'* with the pipe E, through which the steam is conducted away from the cooler to the place of use. The separating-chamber F is situated above the cooler and preferably at such level that it will be partly filled with water, the water of course standing in the chamber F at the same level as it does in the drum *a'*. Suitable provision is made, as the dam *x*, to prevent the water flowing from the chamber F into the steam-pipe E. G is a draw-off pipe connected with the water-space of the cooler and provided with a suitable stop-valve *g*.

With this description of the apparatus its operation may be stated. The valve *c'* in the water-pipe C being opened, the water-space of the cooler will be flooded with water from the boiler, and the temperature of the cooler will be approximately that of the water within the boiler. If now the valve *d'* be opened, superheated steam from the drum *a'* will pass into the steam-space of the cooler and out through the pipe E. On account of the excess of the temperature of the steam over that of the water in the cooler evaporation will take place on the water side and from the surface exposed in the chamber F, such evaporation resulting in a lowering of the temperature of the cooler, and consequently of the steam which may pass therethrough. By reason of the connection of the evaporating-chamber F with the pipe E the steam that is given off from the surface within the chamber F passes directly into the pipe E, commingling with the steam that has passed through the cooler and further reducing its temperature. By suitably proportioning the cooling-surface the desired reduction of temperature can be effected. The apparatus when connected as described is entirely automatic in operation and needs no attention.

If the amount of steam drawn through the

cooler B is very small, it becomes possible to reduce the temperature of the steam delivered through the pipe E to that of saturated steam; but it can never be less than such 5 temperature. There is thus produced an apparatus which by suitable designing can be made to automatically deliver steam at any temperature between that of the superheated steam produced at the generator A 10 and that of saturated steam coming from the same generator.

When the apparatus is put into operation, it is necessary to first draw off through the pipe G the cold water that might be standing 15 therein, allowing the cooler to fill with water from the boiler until it attains the desired temperature, which will of course be that incident to the pressure maintained in the generator A.

20 The apparatus I have just described is the preferred form of my invention. In Fig. 2 I have shown a different embodiment, which I will now describe. Here the steam-generator A is similar to that shown in Fig. 1. 25 The cooler differs in this, however, that the end water-spaces are united only by means of the water-tubes v^2 , the pipe f being entirely omitted. The steam-space b' of the cooler is connected by the pipe D with the generator, 30 as in Fig. 1. The water-pipe C is provided with a float-valve c, arranged to maintain within the water-space of the cooler a constant water-level, this being sufficiently below the top of the cooler to afford an ample 35 evaporating-space. The water-pipe C may and usually will connect with the water-space of the steam-generator A, as represented in Fig. 1, although this is not essential, as the water for the cooler can be taken from 40 another source. The advantages, however, of taking the water from the same source as that of the steam-supply delivered through the pipe D will of course be apparent. The space above the water-level maintained 45 within the cooler is connected with the steam-pipe E by a pipe connection f^2 , through which the steam or vapor that rises from the surface of the water is conducted into the steam-pipe E, the pipe f^2 being connected 50 with the upper portion of one of the water-heads b.

It will be understood that in this form of my invention the water-level is maintained through the action of the valve device c instead of by gravity, as in Fig. 1 construction. 55 The principle of operation of the apparatus (shown in Fig. 2) can be understood without further explanation.

It will be apparent from the foregoing description, taken in connection with the drawings, that my invention is not limited to a specific apparatus. I, however, do not herein deem it necessary to illustrate and de-

scribe further modifications or variations from what is shown, it being understood that 65 the principle of the invention is capable of embodiment in a variety of forms or apparatus.

What I claim is—

1. The combination of a steam-generator 70 and superheater, a cooler having a water-space and a steam-space, a steam connection between the superheater of the steam-generator and the steam-space of the cooler, means for maintaining water within the 75 cooler, a steam-pipe E leading away from the cooler, and a connection F between the water portion of the cooler, above the water-level and the said steam-pipe E, substantially as set forth.

2. The combination of a steam-generator and superheater, a cooler comprising a water-space and a steam-space, a water connection between the steam-generator and the water-space of the cooler, a steam connection between the superheater of the generator and the steam-space of the cooler, a steam-pipe E leading away from the cooler, and a connection between the water-space of the cooler, above the water-level, and the said pipe E, 80 substantially as set forth.

3. The combination of a steam-generator and superheater, a cooler having a water-space and a steam-space, means for maintaining water at a desired level within the 95 water-space of the cooler, a separating chamber or space above the water-level of the water-space of the cooler, a steam-pipe connecting the superheater with the steam-space of the cooler, a steam-pipe E leading away from the 100 steam-space of the cooler, and a pipe or conduit uniting the evaporating chamber or space with the said pipe E, substantially as set forth.

4. The combination of a steam-generator 105 and superheater, a cooler of the surface-condenser type having a water-space and a steam-space, and formed with an evaporating chamber or space above the level of the water in the water-space, means for supplying the water-space of the cooler with water from the steam-generator, a steam connection between the superheater and the steam-space of the cooler, a steam-pipe E leading away from the cooler, and a connection between the evaporating space or chamber of the cooler and the said pipe E, substantially as set forth.

5. The combination of a steam-generator and superheater, a cooler B having a water-space and a steam-space, a connection between the water-space of the generator and the water-space of the cooler, a connection between the superheater and the steam-space of the cooler, a steam-pipe E leading away 125 from the cooler, a separating-chamber F hav-

ing circulating connections with the water-space of the cooler, this chamber being situated at such height that the water-level therein will correspond with the water-level in the steam-generator, and a connection between the chamber F and the pipe E, substantially as set forth.

In testimony whereof I affix my signature in presence of two witnesses.

MINOTT W. SEWALL.
